UNITED STATES PATENT OFFICE.

ROELOF DE BOER AND HENRI WILLEM DE VOGT, OF HEEMSTEDE, NETHERLANDS.

OTTER BOARD FOR FISHING NETS.

Application filed August 18, 1924. Serial No. 732,814.

To all whom it may concern:

Be it known that we, ROELOF DE BOER and HENRI WILLEM DE VOGT, both subjects of the Queen of the Netherlands, residing at 5 Heemstede, the Netherlands, have invented certain new and useful Improvements in and Relating to Otter Boards for Fishing Nets, of which the following is a specification.

The invention relates to otterboards for 10 fishing nets.

The otterboards are generally used for the purpose of giving the cables or nets, to which they are connected, a certain deviation from the direction in which the boards 15 are trailed.

Frequently they are employed in connection with trawl nets for ground fishing. Though the invention more especially relates to this kind of board, it is not restricted thereto, but otterboards constructed in accordance with the principle of the invention may be used in all those cases in which cables or nets should obtain a direction or spreading, deviating from the towing direction of the board.

The invention consists in an otterboard formed as a flat, preferably oblong, box both of the widest longitudinal walls of which meet each other at the short sides in such a 30 way that a section through these walls in the trailing direction shows a flat inner wall and a convex outer wall with the meeting edges of the walls rounded.

By this construction of the board a greater 35 sheering action is obtained than with any other otterboard of the known kind because the experience gained in modern aero-technics is taken into account and only the smallest possible resistance arises during the 40 trailing of the board through the water.

Moreover, the said formation of the board makes it possible to rebuild in a simple way and at low cost existing flat boards.

In employing the board as an otterboard 45 for ground nets it has the advantage of being wide, so it will easily maintain its normal upright position and not catch behind stones on rocky ground nor cut grooves in a weak bottom and increase the resistance.

The invention and its various features 50 will be more fully understood with reference to the accompanying drawings, illustrating an otterboard for ground nets by way of example:

Figure 1 is a side elevation;

Figure 2 a horizontal section on the line II—II in Figure 1, and

Figure 3 a vertical section on the line III—III in Figure 1.

The board consists of a flat wooden inner 60 wall 1 and a bent wooden outer wall 2. The latter is constructed in accordance with the theory of the bearing surfaces of aeroplanes and by this reason a minimum resistance during the towing through the water is obtained with a maximum sheering action.

The walls 1 and 2 are connected at the front side to a stem post 3 and at the rear side a filling piece 4 is provided. By this construction it may be noted that the flat 70 box formed comprises two relative wide longitudinal walls which meet each other at the ends, namely, at the stem post 3 and the filling 4 so that a horizontal section reveals the flat inner wall and the convex 75 outer wall with the forward and rearward edges rounded.

At the top the walls are closed by a cover 5 and at the bottom they are connected to a keel 6. This keel of preferably semicircular section is made of cast steel and its outer 80 surface, as far as it extends beyond the walls, is provided with a lining of hard rubber 7.

Between the walls a stiffening frame of 85 angle iron is provided, the longitudinal angle irons 8 being located directly against the walls and the vertical angle irons 9 being connected to filling pieces 10 between the walls.

Moreover, at the outside of the walls vertical stiffening strips 11 are provided at the place of the filling pieces 10; two diagonals of flat iron 12 against the flat inner wall 1 are provided with holes 13, 14, for 95 attaching the ground rope and the headline of the net.

The keel 6 is over its whole length provided with a vertical stiffening rib 15 and curved at the front side. The board may be 100 connected to the towing rope by means of the braces 16, 17.

Having now particularly described and ascertained the nature of our said invention and in what manner the same is to be performed, we declare that what we claim is:

1. A box-shaped otterboard for ground fishing, a horizontal section of which shows a flat inner wall and a convex outer wall.

2. Improved otterboard to be used in 110

trawling and other similar purposes which is formed as a flat box both longitudinal walls of which meet each other at the short sides in such a way that a section through these walls in the trailing direction shows a flat inner wall and a convex outer wall, and the meeting edges of the walls being rounded.

3. A box-shaped otterboard for ground fishing showing in horizontal section a flat longitudinal inner wall and a convex longitudinal outer wall, said walls being rounded at their meeting edges, a cover interconnecting the walls at the top, a keel of resistant material interconnected with the bottom of

the walls, and a stiffening means within said keel.

4. A box-shaped otterboard for ground fishing including spaced longitudinal walls, a cover connecting the walls at the top, a metal stiffening frame arranged inside the cover, a metal keel semicircular in cross section connected at the bottom of the walls and extending throughout the length thereof, and a lining of hard rubber provided about the keel.

In testimony whereof we affix our signatures.

ROELOF DE BOER.

HENRI WILLEM DE VOGT.
